(57) **CLAIM**

The ornamental design for a boundary fence strainer as shown and described.

DESCRIPTION

FIG. 1 is a bottom front perspective view of a boundary fence strainer showing my new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and,

FIG. 8 is a top left side perspective view thereof.

The portions of the design that are broken away in FIGS. 1 and 4-8 represent indefinite length.
